(57) CLAIM

The ornamental design for a tent, as shown and described.

DESCRIPTION

FIG. 1 is a front, perspective view of a tent.

FIG. 2 is a back, perspective view of the tent of FIG. 1.

FIG. 3 is a front view of the tent of FIG. 1.

FIG. 4 is a rear view of the tent of FIG. 1.

FIG. 5 is a left view of the tent of FIG. 1.

FIG. 6 is a right side view of the tent of FIG. 1.

FIG. 7 is a top view of the tent of FIG. 1; and,

FIG. 8 is a bottom view of the tent of FIG. 1.

The broken lines shown in the figures are for the purpose of illustrating portions of the tent and from no part of the claimed design.
